UNITED STATES PATENT OFFICE.

HENRY J. LAMPERT, OF ST. LOUIS, MISSOURI, ASSIGNOR TO LOOSE-WILES BISCUIT COMPANY, OF ST. LOUIS, MISSOURI, A CORPORATION OF MISSOURI.

DISPLAY-STAND.

1,109,765.

Specification of Letters Patent.

Patented Sept. 8, 1914.

Application filed September 6, 1913. Serial No. 788,398.

To all whom it may concern:

Be it known that I, HENRY J. LAMPERT, a citizen of the United States, residing at St. Louis, Missouri, have invented a certain new and useful Improvement in Display-Stands, of which the following is a full, clear, and exact description, such as will enable others skilled in the art to which it appertains to make and use the same.

10 This invention relates to display stands or racks for holding articles of merchandise that are offered for sale.

One object of my invention is to provide a neat and ornamental display stand that 15 can be shipped in "knockdown" form to retail merchants and then assembled or set up easily without the aid of tools or removable fastening devices.

Another object is to provide a strong and 20 rigid display stand for packages of biscuits, crackers or similar articles that can be manufactured at a low cost and which is so designed that ample space is provided on the members of the stand for receiving advertisements relating to the goods or merchandise displayed on the stand.

Other objects and desirable features of 25 my invention will be hereinafter pointed out.

30 Figure 1 of the drawings is a perspective view of a display stand constructed in accordance with my invention; Fig. 2 is an inverted perspective view of said stand with the shelves removed; Fig. 3 is a vertical sectional view of the stand; Fig. 4 is a detail sectional view illustrating the means that I prefer to use for connecting the shelves to the legs of the stand; Fig. 5 is a horizontal sectional view taken on the line 5—5 of Fig.

35 Fig. 4; Fig. 6 is a detail sectional view illustrating the means that I prefer to use for connecting the legs to the top of the stand; and Fig. 7 is a sectional view taken on the line 7—7 of Fig. 6.

40 Referring to the drawings which illustrate the preferred form of my invention, A designates the legs of the stand, B designates the top, and C designates the shelves of which there are two. The exact number 45 of shelves is, of course, immaterial so far as my invention is concerned, and it is also immaterial whether the stand is rectangular shape and provided with four legs or triangular shape and provided with three legs.

50 The legs, top and shelves of the stand are

preferably formed from sheet metal and they are connected together in such a manner that the stand can be disassembled and shipped in knockdown form to a retail merchant and then assembled easily by the merchant without the aid of tools or detachable fastening devices. The top B preferably consists of a rectangular-shaped piece of sheet metal 1 whose edge portions are turned downwardly so as to form shallow flanges 2 60 that are connected by rivets 3 or in any other suitable manner to a strip of metal 4 that extends clear around the sheet 1 so as to reinforce and strengthen same and also form a deep flange that gives the top of the 65 stand a substantial and solid appearance and also serves to hide from view the connections between the legs and said top. Said strip 4 preferably extends slightly above the top surface of the sheet 1 so as to form a 70 lip 5 at the edge of the top, as shown in Fig. 6, that prevents the packages or articles displayed on the top of the stand from falling off of the same. The shelves C are of similar construction, and each is formed from 75 a piece of sheet metal 1^a, whose edge portions are flanged and permanently connected to a strip of metal 4^a arranged in such a manner that the upper edge of same will project slightly above the top surface of the 80 sheet 1^a and thus form a retaining lip around the edge of the shelf. The legs A are approximately right angle shape in cross section, and while they may be formed from pieces of lightweight angle-iron I prefer to 85 form them from pressed metal so that the stand will be light, the lower ends of said legs flaring outwardly at 6, as shown in Figs. 1 and 3, so as to impart stability and 90 also an ornamental appearance to the stand. 95

The legs A are detachably connected to the top B of the stand and the shelves are detachably connected to said legs so as to enable the parts of the stand to be disassembled and assembled easily. In the 100 preferred form of my invention as herein shown, each leg is provided at its upper end with a laterally projecting flange 7 that slips under a strap 8 connected to the under side of the top of the 105 stand, as shown in Fig. 2, said flange 7 being formed from a piece of metal that fits between the side portions of the leg and which has depending wings 9 that are connected by rivets or in any other suitable 110

manner to the side portions of the leg. By forming the legs in this manner I obtain rigid legs whose upper ends have a comparatively large bearing area on the under 5 side of the top of the stand but I do not wish it to be understood that my broad idea is limited to such a construction for the legs could be detachably connected to the top of the stand in various other ways without departing from the spirit of my invention. 10 The corner portions of the shelves C fit inside of the legs A, which are angle-shaped in cross section, thus securely bracing the legs. Said shelves are connected to the legs 15 by means of clips 10 on the legs that lap over the depending flanges 4^a on the shelves, the clips herein shown being formed from short strips of metal that are riveted or otherwise connected to the legs and which 20 are bent laterally away from the legs, as shown in Figs. 3 and 4, so as to form spaces in which the vertical flanges at the edges of the shelves can fit snugly.

In assembling the stand the legs are first 25 connected to the top B by slipping the cap pieces or flanges 7 at the upper end of the legs underneath the straps 8 on the under side of the top of the stand, and thereafter the shelves C are arranged between the legs 30 and forced downwardly so that the clips 10 on the legs will embrace the depending flanges 4^a on the shelves. To disassemble the stand it is simply necessary to remove the shelves and then detach the legs from the 35 top B.

A stand of the construction above-described is light and strong and it can be manufactured at such a low cost that a

manufacturer of biscuits, crackers or other small merchandise that is put up in package 40 form can afford to furnish the retail merchant with stands for displaying the manufacturer's goods.

The stand can be shipped in knockdown form, and when it is received by the retail 45 merchant it can be assembled or set up easily without the aid of tools or detachable fastening devices.

The stand presents a neat and ornamental 50 appearance, and the wide flanges on the top and shelves and the wide side portions of the legs not only give the stand a solid substantial look but they also afford ample space for advertising matter relating to the goods or merchandise displayed on the 55 stand.

Having thus described my invention, what I claim as new and desire to secure by Letters Patent is:

In a knockdown display stand, a sheet 60 metal top provided on its under side with a pocket, a leg of angle-shape in cross section whose upper end abuts against the lower side of said top, and a laterally projecting pressed metal member on said leg 65 that fits in said pocket, said member having wings that are bent downwardly from said member and connected to the side portions of said legs.

In testimony whereof I hereunto affix my 70 signature in the presence of two witnesses, this third day of September, 1913.

HENRY J. LAMPERT.
